UNITED STATES PATENT OFFICE.

LEN ALBERT BANTA, OF CLEARFIELD, PENNSYLVANIA.

CHIMNEY-VENTILATED SHELL FOR REFRIGERATORS.

Application filed January 27, 1923. Serial No. 615,329.

To all whom it may concern:

Be it known that I, LEN ALBERT BANTA, a citizen of the United States, residing at Clearfield, in the county of Clearfield and 5 State of Pennsylvania, have invented certain new and useful improvements in Chimney-Ventilated Shells for Refrigerators; and I do hereby declare the following to be a full, clear, and exact description of the 10 invention, such as will enable others skilled in the art to which it appertains to make and use the same.

This invention relates to an improved refrigerator structure for use principally in 15 connection with commercial refrigerators or cooling rooms such as are used by butchers and other dealers in perishable food products.

The object of the present invention is to 20 provide for the efficient and adequate exterior ventilation of the box or cooling chamber and, particularly, the bottom of said chamber. Other objects will more particularly appear in the course of the detailed 25 description.

The invention consists in the novel construction, arrangement and combination of parts as hereinafter more particularly described.

30 One sheet of drawings accompanies this specification as part thereof in which like reference characters indicate similar parts throughout.

Figure 1 is a horizontal cross sectional 35 view through a refrigerator embodying the present invention, and

Fig. 2 is a vertical elevation with parts broken away to illustrate the construction.

In accordance with my present invention, 40 the refrigerator or cooling box 1 is raised from the floor by a plurality of slats 4 each slat provided with a plurality of transverse passages 5 to permit a free circulation of air

therebetween and constituting, in association with the floor upon which the refrigerator is 45 seated and the bottom of the refrigerator, a chamber or plurality of chambers for the circulation of air. These air chambers intermediate the refrigerator and the floor are in communication with vertical flues 6, 50 permitting the escape of heated and moisture laden air from the top of the refrigerator.

As illustrated in the drawings, the refrigerator 1 is constructed from a plurality of 55 panel sections secured adjacent their edges as by cleat strips 2 and having finishing strips 3 to enclose the corners thus formed and constitute flues 6 which said flues communicate with the air chambers located intermediate the bottom of the refrigerator and the floor.

Having thus fully described my invention, I claim:

1. A refrigerator having a bottom, an enclosed air space below and coextensive with the bottom and a vertical flue coextensive in height with the refrigerator and communicating with said space at its bottom and having its top open to the atmosphere. 65

2. A refrigerator comprising a plurality of sections joined adjacent their edges to form a chamber and exterior edge channels, means for spacing the bottom from the floor of the building and closure members 75 secured adjacent the lower horizontal and the vertical edges to enclose said space between the bottom and floor and said exterior vertical edge channels whereby the latter constitute vertical flues coextensive in 80 height with the refrigerator and in communication with said enclosed bottom space to permit a circulation of air exteriorly of the refrigerator housing proper.

LEN ALBERT BANTA.
